UNITED STATES PATENT OFFICE.

HARRY HINERMAN, CHARLES MEYERS, AND IRA E. EWING, OF WHEELING, WEST VIRGINIA.

VACUUM-PRODUCING DEVICE FOR SUCTION CLEANERS.

Application filed November 28, 1921. Serial No. 518,282.

To all whom it may concern:

Be it known that we, HARRY HINERMAN, CHARLES MEYERS, and IRA E. EWING, citizens of the United States of America, and residents of Wheeling, county of Ohio, and State of West Virginia, have invented certain new and useful Improvements in Vacuum-Producing Devices for Suction Cleaners, of which the following is a specification.

10 This invention relates broadly to cleaning apparatus of the vacuum type, and more specifically to a vacuum producing device for such apparatus.

The primary object of the invention is to provide an improved construction of apparatus wherein a current of water under pressure derived from an ordinary service line may be utilized for creating and maintaining the powerful suction required in cleaning apparatus of the vacuum type.

A further object is to provide a vacuum producing device of the character mentioned having conveniently adjustable means whereby regulation of the vacuum may be effected.

A still further object is to provide an apparatus of which the vacuum chamber may comprise a single section or may be composed of a plurality of sections, the formation being such that any number of such sections may be employed, multiplication of the sections tending to increase the efficiency of the vacuum.

With these and other objects in view, the invention resides in the features of construction, arrangement of parts and combinations of elements which will hereinafter be exemplified, reference being had to the accompanying drawings, in which—

40 Figure 1 is a longitudinal sectional view of the invention, and—

Figure 2 is a fragmentary section on line 2—2, Fig. 1.

Referring to said drawings, 1 indicates a cylindrical shell or casing which may be employed alone or in association with one or more similar casings 1' arranged in a connected series, the same having a form adapted to allow of its use as a unit in a structure embodying any number thereof. The apparatus will herein be described as a two-unit structure, although, as indicated, a lesser or greater number of units may be employed.

55 The casing 1 has its upper end closed by a head or cap 2 and has attached to and

depending from its lower end the similar casing 1'. This latter casing has attached at its lower end a waste pipe 3 leading to a drain, sewer or other outlet.

The interiors of said casings together 60 constitute a vacuum chamber, and each of said casings has formed thereon one or more tubular arms or branches 4 adapted to be connected to pipes 5 leading to suitable points within the building, such pipes being 65 designed to have attached thereto the flexible tube of a vacuum cleaner.

Disposed concentrically within the interior of the casing 1 is the upper portion of a contracted throat member 6 having a body 70 of relatively small diameter and having its upper end flared outward to meet the casing walls, presenting a gradually inclined mouth. Said member may be cast integral with the casing 1, but is preferably threaded 75 into place within said casing with its mouth end located a suitable distance below the branches 4 and with its lower end extending a suitable distance into the casing 1'.

Directed centrally through the cap 2 is an 80 adjustable vertically disposed tube 7 which carries upon its lower end a spray nozzle 8 having a discharge opening 9 of conical form relative to which a conical, or bell-shaped, valve 10 is adjustable for controlling 85 the flow of water therethrough. Said valve is carried upon the lower end of a valve stem 11 which is adjustable vertically in a valve casing 12 that is mounted upon the upper end of the tube 7 and that has a side-opening 90 13 through which water is admitted under pressure from the water-service line.

The valve 10 is designed to be adjusted with respect to the spray nozzle for directing water in the form of a circular spray 95 against the inclined surfaces of the upper end, or mouth of the throat member 6 for producing a partial vacuum whereby a strong suction is exerted for taking up dirt and foreign matter through the cleaner nozzle and conducting the same to the vacuum chamber 1, whereupon it is caught by the water issuing from the spray nozzle and is discharged downward with the latter to the drain or sewer.

The unit or section 1', coupled to the unit 1 as aforesaid, has one or more branches 4', any or all of which may either be plugged or connected in lines leading to suitable points within the building. Said 110

unit 1' has a throat member 6' which is similar to the member 6, except that the former is plain whereas the latter has threaded upon its lower end a nipple 14 providing a small chamber 16 to which water under pressure is conducted, as through a small pipe 15 directed inward through the casing 1'. A contracted passage 17 is formed between the lower end portions of the throat member 6 and the nipple 14 through which the water admitted to the chamber 15, as aforesaid, is discharged in a circle spray within the mouth of the throat member 6' for increasing the vacuum produced, as aforesaid, by the spray from the nozzle 8.

As is obvious, the volume and the force of the water which impinges upon the throat members 6 and 6' may be regulated by adjustment of the valve 10 and adjustment of the nipple 14 respectively.

What is claimed is—

A vacuum producing device comprising a plurality of vertically aligned casing sections having connection with a drain, the uppermost section having its upper end closed, each of said sections having air-inlet branches, a contracted throat member disposed concentrically within each of said

sections below said branches, each of said members having its upper end flared outward into engagement with the adjacent casing section and presenting a widely flared mouth, a tube extending centrally through and adjustable in the closed end of the upper casing section, a water-inlet valve 30 casing surmounting said tube, a stem adjustable in said valve casing, a valve carried by said stem, a nozzle carried by the lower end of said tube, said valve being adapted to be positioned with respect to the discharge opening of said nozzle through adjustment of said stem for controlling the velocity of the water admitted through said opening, a nipple carried by the lower end of the uppermost of the throat members and providing a chamber having a contracted discharge passage annular to said member, and means admitting water to said chamber.

In testimony whereof we affix our signatures in presence of a witness.

HARRY HINERMAN.
CHARLES MEYERS.
IRA E. EWING.
